(57) **CLAIM**

I claim the ornamental design for a beverage container
insulator, as shown and described.

DESCRIPTION

FIG. 1 is a perspective view of a first embodiment of a
beverage container insulator embodying my new design and
showing an assembled state thereof for accommodating a
beverage container;

FIG. 2 is a front elevation view thereof, the rear, left and
right elevation views being mirror images thereof;

FIG. 3 is a bottom view thereof;

FIG. 4 is a top view thereof;

FIG. 5 is an exploded perspective view thereof, showing a
beverage container in broken lines accommodated therein;
FIG. 6 is a front elevation view of the first embodiment of
the beverage container insulator showing two components
thereof in an interconnected condition, the rear, left and right
elevation views being mirror images thereof;

FIG. 7 is a cross sectional view thereof taken along line 7-7
of FIG. 6;

FIG. 8 is a perspective view of a second embodiment of the
beverage container insulator embodying my new design and
showing an assembled state thereof for accommodating a
beverage container;

FIG. 9 is a front elevation view of the second embodiment
of the beverage container insulator, the rear, left and right
elevation views being mirror images thereof;

FIG. 10 is a bottom view of the second embodiment of the
beverage container insulator;

FIG. 11 is a top view of the second embodiment of the
beverage container insulator;

FIG. 12 is an exploded perspective view of the second
embodiment of the beverage container insulator, showing a
beverage container in broken lines accommodated therein;

FIG. 13 is a front elevation view of the second embodiment
of the beverage container insulator showing two components
thereof in an interconnected condition, the rear, left and right
elevation views being mirror images thereof; and,

FIG. 14 is a cross sectional view of the second embodiment
of the beverage container insulator, taken along line 14-14 of
FIG. 13.

The beverage container, shown in broken lines, forming no
part of the claimed design.
